UNITED STATES PATENT OFFICE

JOHN H. KOLTS, OF CRAFTON, PENNSYLVANIA, ASSIGNOR TO PITTSBURG WATER HEATER COMPANY, OF PITTSBURGH, PENNSYLVANIA, A CORPORATION OF NEW JERSEY

THERMOSTATIC CONTROL VALVE

Application filed March 24, 1928. Serial No. 264,325.

This invention relates to thermostatic control valves particularly adapted for use in connection with ovens or water heaters, in which latter connection it will be described herebelow.

Among the primary objects of the invention are: simplicity of construction and assemblage; positive action; ease of initial setting; and convenient and positive adjustment to accommodate it to varying operating conditions.

How the foregoing, together with other objects and advantages are obtained will be clear to those skilled in the art by a consideration of the following description taken together with the accompanying drawings which illustrate a convenient embodiment of the invention.

Of the drawings:

Fig. 1 is somewhat diagrammatic and shows the application of my improved device to a water heater;

Fig. 2 is a sectional view through the thermostat and valve mechanism of my invention, the view being taken substantially on the line 2-2 in Fig. 3;

Fig. 3 is a cross sectional view through the valve body as indicated by the line 3-3 in Fig. 2; and

Fig. 4 shows a view similar to that shown in Fig. 2, but illustrating the valve and the adjusting mechanism in different positions.

Referring now particularly to Fig. 1, the reference numeral 5 indicates a water heater tank, and the numeral 6 refers to my improved device, as a whole, which is shown as being provided with a thermostatically responsive element 7 extending into the tank to respond to the temperature of the water therein. Gas is supplied to the valve mechanism through the pipe 8 in which a stop cock 9 is provided, and the gas is conveyed from the valve mechanism to the burner 10 positioned below the tank 5 through the pipe 11.

In referring more particularly to Figs. 2 and 3, it will be observed that the valve mechanism comprises a hollow body 12 having connection portions 13 and 14 adapted to receive the ends of the pipes 8 and 11, respectively. The interior of the valve body 12 is divided, by a partition 15, into two chambers 16 and 17 with which the connections 13 and 14, respectively, communicate. The partition 15 is provided with a circular opening 18 around which a valve seat 19 is provided. The passage of gas from the chamber 16 to the chamber 17 (through the opening 18) is controlled by a circular valve 20 which is yieldingly urged toward the seat 19 by the spring 21. The spring 21 reacts against a screw cap 22 which is provided in the valve body to permit assembling of the valve parts as well as to provide access for inspecting, cleaning or repairing the valve parts.

Opposite to the cap 22 the body 12 is provided with a valve stem bearing 23 which is arranged concentrically with respect to the opening 18. A valve stem or pin 24 extends through the bearing 23 and is provided with a plurality of circumferential grooves 25 for preventing leakage through the bearing 23 around the valve stem. One end of the valve stem is engaged or received by an opening or pocket 26 formed in the valve 20, this pocket being slightly larger than the valve stem so that a loose engagement is provided between the valve and its stem. Thus the spring 21 always accurately seats the valve when it is closed.

A bushing 27 is supported from the valve body by the projections or arms 28 and is provided with a threaded opening adapted to receive the nipple 29 by means of which the whole mechanism is supported on the water tank (see Fig. 1). A second threaded opening, of smaller diameter, is provided in the bushing to receive the externally threaded end of the thermostatic tube or element 7.

At its outer end the tube 7 is internally threaded to receive the threaded plug member 30 and this plug 30 is provided with an internally threaded opening adapted to receive the valve actuating rod or connection 31. The cooperating threads on the tube 7 and the outside of plug 30 have a different pitch than that of the cooperating threads on the rod 31 and the inside of the plug 30. 5 They are so arranged for a reason to be noted herebelow.

The rod 31 extends inwardly through the tube 7 to abut against the valve stem 24 and thus serves to transmit the movements 15 of the outer end of the tube 7, which are caused by its expansion and contraction, to the main or controlling valve 20. A collar 32 may be provided in the inner end of the tube for centering the rod 31 with respect 20 thereto and a lever or pointer 33 is secured in the rod 31 to facilitate manual adjustment of the mechanism for various operating conditions.

A cylindrical by-pass valve chamber 34 is 25 formed in the valve body 12, the same being positioned adjacent to the partition 15. It has an opening or port 35 at its inner end communicating with the interior of the valve body at one side of the partition 15 and a 30 substantially radially extending port 36 through its cylindrical wall communicating with the interior of the body at the other side of the partition. The cylindrical valve 37 is adapted to be inserted into the chamber 34 through its outer and open end, such end being internally threaded to receive the retaining bushing or collar 38. This collar may be rigidly secured in place by means of the nut 39. The valve 37 has a slotted stem 40 extending therefrom through the collar for purposes of making adjustments. A cap 41 may be provided to prevent leakage and protect the valve stem. The by-pass valve proper 37 has a central bore which is open 45 at one end to the port 35. It is also provided with a port 42 adapted to register with the port 36 in the cylindrical chamber wall 34.

In considering the operation of my improved control device it should be borne in 50 mind that the burner 10 is of a type adapted to operate as a pilot as well as a main burner and that the flow of gas through the valve mechanism by way of the by-pass is regulated (by turning the port 42 in the valve 55 37 more or less into or out of registry with the port 36) to that quantity which is necessary for pilot purposes.

When the device is first assembled an 60 initial adjustment of the thermostat mechanism is made. This may be accomplished in a simple and convenient manner as follows:

The entire valve with the exception of 65 the plug 30, being assembled, the plug 30 is screwed into the threaded end of the tube

7, the threaded end of the rod 31 is started into the plug and the plug is advanced (while retaining the rod 31 against rotation with the indicating pointer 33 in the "cold" position, as shown in Fig. 2) until the inner 70 end of the rod 31 approaches to within about five one thousandths of an inch (.005") of the valve stem 24. (See 43 in Fig. 2.) The rod 31 is advanced, of course, in view of the difference of pitch of the threads on the inside and outside of the plug 30. This adjustment when made at average atmospheric temperatures provides an operating temperature range which is suited to normal 75 operating conditions.

It is to be understood, of course, that the service to which the device is to be put might make it desirable to adjust the valve for a different temperature range, this being accomplished by advancing or retracting the 80 plug member 30. Furthermore, the initial or temperature range adjustment would vary where, in order to adapt the mechanism to various types of service, the expansion tube is made of various materials whose coefficients of expansion differ. In any case, when 85 the initial adjustment is made, the plug member 30 is secured as against rotation, preferably by applying the solder indicated at 44 in Fig. 2. When the mechanism is so adjusted and is applied to the water heater (or 90 to whatever apparatus with which it is to be used) the rod 31 is turned, by means of the pointer 33, to set the thermostat to maintain any average water temperature desired. 95

The actual mechanical operation or movement of the device is quite simple and obvious, the valve 20 being gradually opened by the rod 31 as the thermostatic element cools and contracts and being closed by the spring 21 as the element is heated and expands. Fig. 4 shows the pointer 33 in the upper or "hot" position and also the valve 20 in open position.

Thus, my device, being composed of relatively few and easily assembled parts, provides for effective initial temperature range adjustment when assembling the parts, as well as for convenient average temperature adjustment while the device is installed and 115 in operation.

I claim:—

1. In a device of the character described, a valve, an internally threaded thermostatic expansion tube, an externally threaded valve operating member extending into the tube, the threads in said tube having a different pitch than those on said valve operating member, and an internally and externally threaded member associated with said tube and said valve operating member and cooperating with their threads to provide an adjustment of the said operating member with respect to the said tube.

2. In a device of the character described

the combination of a valve body, a valve therein, a stem engaged by said valve, a thermostatically responsive element for controlling said valve secured at one end with respect to the valve body, a member adjustable with respect to the other end of said element and having a part screw threaded, and a connection member having threads engaging those of said part and extended to abut against said valve stem, together with means for manually rotating said connection member.

5 In testimony whereof I have hereunto signed my name.

10 JOHN H. KOLTS.
